UNITED STATES PATENT OFFICE.

ARTHUR H. LEHMAN, OF LAS ANIMAS, COLORADO.

COMBINED MATCH-SAFE AND ASH-TRAY.

1,162,622.

Specification of Letters Patent.

Patented Nov. 30, 1915.

Application filed April 7, 1914. Serial No. 830,250.

To all whom it may concern:

Be it known that I, ARTHUR H. LEHMAN, a citizen of the United States, residing at Las Animas, in the county of Bent and State of Colorado, have invented new and useful Improvements in Combined Match-Safes and Ash-Trays, of which the following is a specification.

The invention relates to match boxes, and 10 has for an object to provide a combined pocket match safe and ash tray.

The invention contemplates, among other features, the provision of a simple structure consisting of few parts which can be 15 readily formed of stamped metal to provide a match safe for containing matches, such as the usual parlor matches or those which come in boxes and are known as safety matches.

20 The invention still further contemplates suitable means forming covers for the match safe and which, when open, will constitute ash trays.

In the further disclosure of the invention 25 reference is to be had to the accompanying drawings, constituting a part of this specification, in which similar characters of reference denote corresponding parts in all the views, and in which:

30 Figure 1 is a perspective view of the match safe, showing the same in closed position; Fig. 2 is a perspective view showing the match safe open, and Fig. 3 is a bottom plan view of the match safe. Fig. 4 is a 35 fragmentary vertical sectional view taken through the structure as disclosed in Fig. 2.

Referring more particularly to the views, I disclose a match safe 10 comprising a holder 11 preferably in the nature of a receptacle having a substantially rectangular configuration and preferably having its bottom 12 rounded. A hinge member 13 projects from the rounded bottom 12 at its medial portion and is adapted to receive there- 40 through a pintle 14. Covers 15 terminate at their inner ends in hinge members 16 and the hinge members of each cover are adapted to register with the hinge member 13, with the pintle 14 passing through the hinge 45 members 16 so that the covers 15 will be swingingly supported on the under side of the holder 11, said covers 15 adjacent the

hinge members 16 being rounded as shown, and also having their free edges 17 rounded. The covers 15 are formed with sides 18 to 55 constitute trays when the covers are in horizontal position as shown in Fig. 2 and one of the covers 15 is provided with a push button clasp 19 adapted to engage a strap 20 on the other cover so that the covers can be 60 locked in closed position and inclose the holder 11 as shown in Fig. 1, it being readily seen that by forming the covers as mentioned their edges will fit closely together to form a smooth surface when the covers 65 are closed. The holder 11 and also the covers 15 are provided with serrations 21 upon which matches can be struck, the said serrations being preferably formed on the outer sides of the holder and the outer faces 70 of the covers.

From the foregoing description it will be apparent that the device described provides a simple and effective pocket match safe for containing matches in the holder 11 and 75 which will be inclosed by the covers 15 when they are in closed position, while the device also comprehends the use of the covers 15 for ash trays when they are open as shown in Fig. 2, the said covers being adapted to lie in opposed relation, with the holder 11 therebetween.

Having thus described my invention, I claim:

A device of the class described comprising 85 a holder having its bottom provided with an exteriorly arranged groove semi-circular in cross section, a pair of covers each having one edge provided with rectangular recesses forming substantially rectangular hinged 90 members, hinged members of one cover being arranged in the recesses of the other cover and adapted to abut the inner walls of the recesses when in open position, and a pintle passing through the extremities of 95 the hinged members and engaging portions of said holder, said pintle lying within the groove of the holder.

In testimony whereof I affix my signature in presence of two witnesses.

ARTHUR H. LEHMAN.
